UNITED STATES PATENT OFFICE.

JOHN AULD, OF CHICAGO, ILLINOIS.

FOUNTAIN BRUSH.

1,413,311.

Specification of Letters Patent. Patented Apr. 18, 1922.

Application filed August 23, 1920. Serial No. 405,229.

To all whom it may concern:

Be it known that I, JOHN AULD, a citizen of the United States, and a resident of Chicago, in the county of Cook, State of Illinois, 5 have invented certain new and useful Improvements in Fountain Brushes, of which the following is a specification.

My invention relates to fountain brushes, particularly to that type for marking on 10 boxes, bales, packages or containers.

Among the important objects of my invention are: to provide improved construction which will prevent leakage especially at the outlet valve mechanism, of ink which 15 will eventually find its way to the outside of the brush and soil the hands of the user; to provide improved adjustable stopper or valve mechanism for controlling the outflow of writing fluid from the brush body; to 20 provide improved arrangement which will enable the ready substitution of one form of marking point for another; to provide simple and practical arrangement which will enable the various parts to be readily assembled or taken part; and in general, to 25 provide a light, simple, neat and easily handled and controlled fountain brush structure.

On the accompanying drawing,

30 Fig. 1 is a side elevational view,

Fig. 2 is a diametral sectional view of the outlet end of the brush,

Fig. 3 is an enlarged plan view of the nozzle,

35 Fig. 4 is a sectional view on plane 4—4, Fig. 2,

Fig. 5 is a side elevational view of a modified form of outlet controlling mechanism,

40 Fig. 6 is a diametral sectional view of such modification,

Fig. 7 is a side elevational view of the marking point and

Fig. 8 is a sectional view on plane 8—8, 45 Fig. 6.

The brush body comprises a combined handle and ink container 10 in the form of a length of tube provided at one end with a cap 11 and at its other end with a fitting 12 for supporting the valve and marking mechanism designated as a whole by 13. In Figs. 1 and 2, one form of fluid discharge controlling mechanism is shown. The fitting 12 has the threaded end 14 which receives the nozzle base 15. The outer end of 50 the nozzle base is closed except for the outlet holes 16, the needle or valve cone 17 ex-

tending axially from the base end and between the outlet holes. The base 15 has the reduced end section 18 which is threaded to receive the nozzle cap 19 which has the central valve port 20 with which the needle or cone 17 co-operates to control the rate of outflow of marking fluid. Surrounding the nozzle structure and secured to the base 15 is the tube 21. This tube serves to support 60 the frame 22 which carries the marking member 23. Besides serving to hold the marking member, this frame is utilized for turning the nozzle cap 19 to control the size of passageway through the port 20. The 65 body of the frame 22 is U-shape to clamp the marking member, and extending from one limb of the body part is the arm 24 which runs downwardly along side of the tube 21 and has the deflection or abutment 25 which 70 by engaging against the side of the tube 21, introduces spring action in the arm so as to permit rotation of the frame 22 but to lock it in adjusted position. The base of the frame 22 within the tube 21 engages between 75 the ears 26 and 27 extending upwardly from the sides of the nozzle cap 19 so that when the frame is turned it will also cause turning of the nozzle cap and opening to greater or less degree of the port 20. Normally, the 80 frame has been rotated by means of its arm 24 to screw down the nozzle cap to cause its port to be closed by the needle port or cone 17. When it is desired to use the brush, the arm 24 is swung around to turn the frame 22 85 and the cap 19 so as to open the port 20 to the desired degree for the passage of ink.

The ink flows through the holes 16 and through the cap 19 and escapes through the port 20, the brush being of course held with 90 the marking end down. The ink then flows along the body of the frame 22 and is received by the marking element 23. This element may be a piece of felt, sponge, bristles or other material inserted between the limbs 100 of the frame 22. As shown in Figs. 1 and 2 the marking element is in the form of a block 23 of felt or other absorbent material in which are secured the brush bristles 28, the bristles being preferably extended entirely through the block and glued or otherwise secured thereto, or merely held by friction. The block of absorbent material will receive the ink from the frame 22 and will 105 convey it to the bristles.

The tube 21 also forms a well for receiving 110 overflow or backflow of ink. If, after a pe-

riod of use, the brush is raised, unused ink may flow back along the brush structure and the frame 22, but such ink will be accumulated in the well formed by the tube 21 and the base 15, and then when the brush is again turned to its operative position, this ink will flow down to be used. Some ink may also leak past the threads which connect the cap 19 with the base 15, but here again the well will receive the leakage and it will ultimately be used for marking purposes. This will prevent any of the ink from reaching the handle part or body of the brush where it could soil the hands of the user.

To enable the user to adjust more accurately for the outflow of ink, the fitting 12 has gauge markings 29 thereon (Fig. 1), the co-operation of the inner end of the arm 19 with these gauge marks informing the user to what degree the ink port 20 is open. As shown in Fig. 1, the end of the fitting 12 is polygonal so that a wrench may be applied for applying or removing the fitting with reference to the container 10. On the sides of this polygonal section, I have shown numerals applied which in this case serve as gauge indications for co-operating with the arm 24.

In Figs. 5, 6, 7 and 8, I have shown a modified construction. Here, like in the constructions of Figs. 1 and 2, the nozzle structure base 15' is secured to the threaded end of the fitting 12' and at its end has the valve pin or cone 17' surrounded by passageways 16', and the nozzle cap 19' threading on to the base member 15' and having the port 20' for co-operating with the valve pin or cone. This modification also has a tube 21' which, however, instead of being rigidly secured to the base 15' has threaded engagement with a flange 30 extending from the base 15' outside of and spaced away from the base end which receives the nozzle cap. This outer flange forms a cup for receiving back flow or overflow of ink or any ink that may escape between the threads which hold the cap to the nozzle base. Between the fitting 12' and the abutment flange 31 on the tube 21' is inserted the compression spring 32 for locking the tube against accidental rotation.

The nozzle cap in the modified structure has the arms 33 and 34 extending therefrom well through the tube 21' so as to receive between them the block 35 of felt or other suitable material for conveying ink. As shown, this marking block or point is seated in the U-shaped frame 36 where it may be held in place by a screw 37 extending through the yoke of the frame and threading into the block. The outwardly deflected ends 38 and 39 on the U-frame extend outwardly through notches 40 and 41 formed in the end of the tube 21'. With this arrangement, turning of the tube 21 will be communicated

by the extensions 38 and 39 to the marking point structure and from there to the arms 33 and 34 extending from the nozzle cap, so that turning of the tube 21' will cause opening or closing of the ink outlet port 20'. In other words, in the construction of Figs. 1 and 2, the marking point supporting frame is directly turned by means of the arm 24 and in the modification of Figs. 5 and 6, the marking point frame and the nozzle cap are turned with the tube 21'. Instead of the felt point 35, brush bristles may be provided as in the construction of Figs. 1 and 2, bristles being usually used when marking is done on rough surfaces while a felt or similar marking tip is provided where marking is to be done on smoother material.

It is evident that instead of the cap 11 at one end of the brush body, a fitting 12 can be provided to which a valve and marking point structure can be applied so that there would be a double ended brush, one end of which could be used for marking on rough surfaces and the other end, for marking on smooth surfaces. The overflow and surplus ink receiving well would then form an important part as they would prevent flowing of ink from the upper marking end to the brush body and to the hands of the user.

Other changes and modifications are, of course, possible which would still come within the scope of my invention. I do not, therefore, desire to be limited to the exact construction, arrangement and operation shown and desired.

I claim as follows:

1. In a fountain brush of the class described, the combination of an ink container, a nozzle base at one end of said container, a cap rotatable on said base, valve mechanism controlled during rotation of said cap on said base for regulating the flow of ink from said container, a tube extending from said base and surrounding said cap, extensions on said cap, a marking point supporting frame extended into said tube to engage with said extensions, a marking point held by said frame, and an arm extending from said frame along side the outside of said tube, said arm enabling turning of said marking point supporting frame and thereby turning of said cap by virtue of engagement of said frame with said extensions.

2. In a fountain brush of the class described, the combination of a tubular ink container, a nozzle base secured at one end of said container, a nozzle cap having threaded engagement with said base, valve mechanism controlled upon turning of said cap on said base to regulate the flow of ink from said container, a tube extending from said base around said cap, extensions on said cap, a marking point supporting frame extended into said tube and engaging between said extensions whereby turning of said

frame will turn said cap to effect adjustment of the ink flow, a marking point held by said frame and extending from the end of the tube, and an arm extending from said frame along the outside of said tube and having spring-locking engagement with said tube, said arm serving as a handle whereby said frame may be rotated and said cap rotated to adjust the flow of ink, said tube 10 also serving as a well for storing overflow or backflow ink.

3. In a fountain brush, the combination of an ink container forming a handle, a base on said container having an outlet opening, 15 a valve extending from said base, a cap movable on said base and having a port for co-operating with said valve to control the outflow of ink from said container, extensions on said cap, and a marking point held 20 between said extensions and prevented thereby from turning relative to the cap, said marking point when turned causing said cap to be rotated to thereby control co-operation of the valve and port.

25 4. In a fountain brush, the combination of a reservoir for ink, a valve base on said reservoir, a valve on said base, said base being apertured for the flow of ink, a cap threaded on said base and having a port for co-operating 30 with the valve to regulate the flow of ink, a tube extending from said base and

forming an ink-tight well with said base for catching and retaining surplus ink, a frame extending from said cap, a brush supported by said frame, an extension on said frame 35 to the exterior of said tube forming a handle whereby said frame may be rotated to in turn rotate said cap and relatively adjust said valve and port to regulate the flow of ink.

5. In a fountain brush, the combination of a reservoir for ink, a base on said reservoir, a valve on said base, ink apertures in said base adjacent said valve, a cap threadedly engaging said base and having a port for co-operating with said valve to regulate the flow of ink, a tube secured to and extending from said base and forming therewith an ink-tight well to catch and retain surplus ink, a frame connected with and extending 50 from said cap through said tube, a brush supported by said frame, and an operating handle formed by extending part of said frame outward and against the outside of the tube, turning of said handle around said 55 tube causing turning of said frame and said cap whereby adjustment is effected between said port and valve and the flow of ink regulated.

In witness whereof, I hereunto subscribe 60 my name this 19 day of August, A. D., 1920.

JOHN AULD.
